SPARK PLUG HAVING A MICA INSULATOR
FOR INTERNAL COMBUSTION ENGINESEnrico Zanzi, Ivrea, Italy; vested in the Alien
Property CustodianApplication October 29, 1940, Serial No. 363,374
In Italy November 21, 1939

1 Claim. (Cl. 123—169)

This invention relates to improvements in spark plugs having a mica insulator for internal combustion engines. The insulator is generally constituted by mica rings fitted on the core and tightly pressed. In spite of the high pressure the current may pass through the capillary interstices between adjacent rings. These rings, in the known constructions, are separated from the metallic core by means of a mica tube, which constitutes a screen preventing leaks of 10-15,000 v. current in a radial direction from the core towards the spark plug body through the rings. Current leaks, however, may occur from the core head to the spark plug body first in an axial direction through the gap between the central mica tube and the ring pack and then in a radial direction through the ring pack.

According to this invention the mica rings are also fitted on a central mica tube coating the core and, moreover, the ring pack is introduced into a mica tube covering the inner wall of the spark plug body; the current accidentally flowing from the core head may pass through the central tube and ring pack and then between the rings but cannot reach directly the spark plug body; it flows to the base of the body passing through a gap between the ring pack and the outer mica tube.

The resistance to the current flow through interstices between mica and mica is thus increased to nearly twice the former resistance.

According to this invention and in view of the fact that the rings, which are in closer proximity to the electrodes are more exposed to be damaged by the current, are subdivided into two concentric rings separated by a wide gap, so that when one of these rings is damaged, the dispersion current is lead on two paths along the axis of the first undivided ring between the core head and the base of the spark plug body.

The annexed drawing shows an embodiment of the invention.

Fig. 1 is an axial section of a spark plug of ordinary construction.

Fig. 2 is an axial section of a spark plug of a similar type but improved according to this invention.

Spark plugs are constituted (Fig. 1) by a body 1 connected to the engine mass and a core 2 connected to the source of power; the body and core are insulated from each other. A mica insulator is preferably used for spark plugs exposed to high temperatures owing to its strength and is generally constituted by a pack of mica rings 3 (Fig. 1) fitted on the core and pressed against the head 2a with the interposition of a mica tube 4

and in many cases also of a copper tube 5 between the mica tube and core. An annular chamber 7 between the ring pack 3 and body 1 forms an extension of the chamber 6 of the spark plug.

Although the mica rings are highly pressed together, a dispersion of 10-1500 v. current may occur through the capillary interstices; the tube 4 prevents a direct dispersion from the core 2; the current may only flow from the head 2a through the narrow gap between the tube 4 and pack 3 and reaches the wall of the body 1 through the annular chamber 7, in which carbonaceous deposits may be collected.

According to this invention the annular chamber 7 is eliminated and the ring pack 3 fitted, as in the former case, on the core 2 with the interposition of a mica tube 4 and a copper tube 5, is of such diameter as to fill completely the cylindrical space in the body 1 (Fig. 2); a mica tube 8 having the same function as the tube 4 and, if desired, a copper tube 9 are interposed between the pack and body. The dispersion current passing from the head 2a through the capillary interstices between the rings and the narrow gap between the tube 4 and pack 3 reaches the base of the body 1 passing through the gap between the rings and tube 8, that is to say it follows a path twice as long as the path in the ordinary construction.

According to a further improvement, the ring pack 3 is provided on the side of the chamber 6 with a wide and deep circular slot 10 forming an extension of the chamber 6 and obtained by subdividing, along a section of the pack, each ring into two concentric rings 3a and 3b; the rings 3a bear on the head 2a of the core and the rings 3b on the shoulder 1a of the body of the spark plug. The current escaping between the head 2a and shoulder 1a must thus follow a path equal at least to twice the depth of the slot 10.

The spark plug may be disassemblable or not and be provided with sparking points of any shape and, generally, various changes may be made in the details of construction without departing from the limits of the invention.

What I claim is:

A spark plug for internal combustion engines, comprising a core of conducting material, a mica tube fitted on said core, a pack of mica rings surrounding said mica tube and having on the spark side a wide and deep axial circular slot, a second mica tube in which said pack of mica rings is introduced and a casing of conducting material surrounding said second mica tube.

ENRICO ZANZI.
